METHOD AND APPARATUS FOR APPLYING COLOR CODED STRIPING TO MINIATURE COMPONENTS

Antonio Ramos, Cumberland, R.I., assignor to General Instrument Corporation, Newark, N.J., a corporation of New Jersey

Filed June 1, 1964, Ser. No. 371,635
20 Claims. (Cl. 117—212)

This invention relates to the marking or color coding of electronic components, and more particularly to a machine for marking microdiodes.

Electronic components are becoming smaller, and have gone from miniature to microminiature. The invention as here illustrated is applied to the marking of a microdiode which has an insulation body only one-tenth inch long, with oppositely projecting lead wires one-half inch long. Components are marked by standardized color code stripes, and in the present case the stripes are to be spaced only twenty-five thousandths of an inch from center to center.

One method of color marking is by hand. A more usual machine method is by indirect transfer of the marking from color print wheels or discs through a rubber surfaced transfer wheel to the component being marked, but this and other methods present great difficulty when making the very narrow and closely spaced stripes here required. It is important to keep the stripes accurate and distinct, and to prevent contact and bleeding between stripes.

The general object of the present invention is to overcome the foregoing difficulties, and to provide a marking machine for tiny components, particularly of microminiature size. In accordance with the present invention a plurality of thin filaments or wires are first coated, and these are guided very close to one another in collateral relation, and are simultaneously moved laterally into contact with the component to be marked.

Further objects of the invention are to control the thickness of the coating on the wire; to eliminate the coating on one side of the wire where it is not used; and to advance the wire a small amount to present a new segment of coated wire for each marking operation.

Another requirement is that the marking be applied to a specified lead of the component. In the case of a diode the marking is to be applied to the cathode lead, it being understood that we deal here with a component the body of which is too small to receive the marking, or is so shaped that it would be difficult to apply the marking. In accordance with another feature and object of the present invention the polarity of the diode is checked as it is placed in the marking machine, so that if wrong it may be reversed to properly polarize the same.

To accomplish the foregoing general objects, and other more specific objects which will hereinafter appear, my invention resides in the marking machine elements, and their relation one to another, as are hereinafter more particularly described in the following specification. The specification is accompanied by drawings in which:

FIG. 1 is a plan view of a marking machine embodying features of the invention;

FIG. 2 is an elevation thereof;

FIG. 3 is a perspective view showing a pedestal on which the component is placed for marking;

FIG. 4 is a fragmentary section showing one of the ink containers for coating a wire;

FIG. 5 is a fragmentary view taken on the line 5—5 of FIG. 4;

FIG. 6 is a section through a coated wire;

FIG. 7 is a fragmentary section through the wires at the printing station; and

2

FIG. 8 is an electrical diagram for the polarity checking circuit.

Referring to the drawing, and more particularly to FIG. 3, the component is a microminiature diode sealed in a plastic housing 12, with oppositely projecting lead wires 14 and 16 having a length of say one-half inch. One lead wire, in this case the cathode lead 14, is to receive the color coded stripes, and in the present case there are five such stripes having a spacing of twenty-five thousandths of an inch, with clearance between stripes of ten thousandths inch.

Referring now to FIG. 2 of the drawing, the apparatus comprises means at 20 to coat a plurality of thin filaments or wires with appropriate colors, there being one filament for each stripe. There is an additional means, in this case a grooved spacer wheel 22, to guide the coated filaments very close to one another in collateral relation. There is also a means, in this case a manually operable handle 24, to simultaneously move all of the coated filaments laterally into contact with and then away from an electronic component at a marking station 26. The wheel 22 is here shown in down position. There is also a means, generally designated 30, to move all of the filaments simultaneously lengthwise a small amount to present new segments of the coated filaments. Thus, the filaments are cyclically moved longitudinally and laterally into contact with successive electronic components placed at station 26.

Considering the machine in greater detail, and referring to FIGS. 1 and 2, there is a pedestal 32 to support a component, with one lead wire exposed to receive the marking. An upright movable mounting plate 34 carries a plurality of reels 36 of thin wire, one for each stripe. In the present case there are five reels for five stripes. If small, the reels may be mounted directly on plate 34, but to avoid winding special small reels, in the present case larger commercially available reels are employed, and are mounted on an arm 38 fixedly secured to and effectively forming a part of the plate 34. Because the commercial reels have appreciable width, as seen in FIG. 1, the arm 38 may be displaced sidewardly from plate 34, as by means of a block 40.

The plate 34 also carries a plurality of ink containers shown at 20 in FIG. 2, and each of these containers terminates in a long thin tube 42, preferably having an inside diameter only a few thousandths of an inch greater than the diameter of the wire. These tubes 42 run at different angles to points preferably closely approaching the grooved spacer wheel 22 previously mentioned.

The plate 34 also carries guide means to guide the wires from the reels 36 through the containers 20 and tubes 42. In the present case there are eyes 44 carried by a bar 46 projecting from the arm 38, followed by sheaves 48 which are coaxial, and which are followed by spaced sheaves 50, one for each wire and ink container. This arrangement is employed in order to bring the wires close together. The eyes 44 represent a first stage of convergence, and the coaxial sheaves provide a second stage of convergence. However, at sheaves 48 the minimum spacing is limited by the sheaves themselves, and accordingly the sheaves 50 are on separate spaced axes, so that they may overlap in axial direction, thereby making it possible to bring the wires to as close a spacing as is desired. This spacing may approach or even equal the final spacing, say twenty-five thousandths of an inch.

The base 52 of the machine carries fixed bearings 54 and 56 (FIG. 1) which carry a plurality of takeup reels or spools 58. These are small in axial direction, and are secured to a common shaft 68, which shaft also carries a ratchet wheel 60. Plate 34 may be provided with a pawl 62 engaging the ratchet wheel 60 as later described. There is a friction brake at 61.

FIG. 2 shows plate 34 in its down position. It is normally urged upward by resilient means, in this case a compression spring 64. The upward motion is limited to a suitable amount, say one-half inch, at the pedestal 32, which is adequate for loading and unloading the pedestal. Handle 24 is fixed directly on plate 34, and serves as a manual means to move the plate downward. However, a treadle may be provided for foot operation, in which case a suitable cord or chain 66 may extend downward to the treadle.

The takeup spools 58 are advanced slightly for each printing movement of the plate, and to facilitate this the plate 34 is preferably pivoted on the axis of ratchet wheel 60, that is, on shaft 68 between bearings 54 and 56. The pawl 62 is preferably faced as shown, so that it moves the ratchet wheel during upward movement of plate 34, but it could be faced the other way.

Referring now to FIG. 5, the ink container 20 may be tapered at its lower end 70 leading to the long slender tube 42. This tube has an inside diameter slightly greater than the diameter of the wire 72. The tube is preferably so oriented that the wire rubs against one side of the tube at the discharge end of the tube, as shown at 74. This is the side of the wire which engages the spacer wheel. Thus, in FIG. 2 all of the tubes 42 are displaced very slightly to the left at their lower ends, in which case the wires are wiped clean on the side engaging spacer wheel 22, and carry ink on the outer sides which come into contact with the component to be marked. This is also shown in FIG. 6, in which wire 72 is coated heavily on the bottom as shown at 76, but is uncoated on top where it engages the grooved spacer wheel 22.

To facilitate adjustment of the inking tubes, each container and tube may be angularly adjustable in the plane of the path of the wire as shown in FIG. 2, or differently expressed, in a plane perpendicular to the axis of the spacer wheel 22. The ink containers are received between spaced strips or holders 120 and 121 shown in FIG. 4. These may be held together and on the plate 34 (FIG. 2) by screws 122. The bottom is closed except for a longitudinal slit 123 through which the tubes 42 pass. The angular position of each container may be locked, as by means of a set screw 124. It will be evident that with this arrangement the tube may be positioned with its lower end toward the left, as viewed in FIG. 2, relative to its wire, thereby accomplishing the desired wiping action shown at the bottom of FIG. 5.

The adjustment of the tubes axially of the spacer wheel 22 may be accomplished at the same time, as by the insertion of shims on one side or the other, and in any event is not critical because the very slight displacement needed at the lower end of the tube may be accomplished by the wire itself, as guided or fixed by the receptive groove of the spacer wheel 22. The shims which may be used are not shown in the drawing.

A convenient way to provide the ink container 20 is to employ the combined body and needle of a conventional hypodermic syringe, the needle size being properly selected for the desired coating thickness. In the particular case shown, the wire has a diameter of thirteen thousandths inch, and the inside diameter of the tube 42 is sixteen thousandths inch, thus providing a coating at 76 (FIG. 6) of three thousandths inch.

The purposes of the slender tube 42 are to limit the amount of fluid to desired thickness, and to remove the fluid from that side of the wire which will not come in contact with the part to be marked. By its capillary nature it also prevents unwanted dripping of the fluid from the lower end of the tube.

Referring now to FIG. 3, the pedestal 32 has a pocket at 80 large enough to receive the body 12 of the microdiode. There is a groove at 82 to receive the lead 16, and a groove at 84 to receive the lead 14, but the pedestal is cut away at 86 to expose part of the lead 14 to the coated wires. This construction is also shown in FIG. 7, the

body 12 being received in pocket 80, the lead 16 in groove 82, the outer end of lead 14 in groove 84, while the inner portion of lead 14 rests on the pedestal, but is exposed to the wires carried by spacer wheel 22.

The marking is to be applied to the cathode lead, and it is therefore necessary to properly polarize the microdiode when placing it on the pedestal. The polarity test may be made in advance, but it is safer and more convenient to check the polarity at the pedestal. For this purpose the pedestal is made of two conductive parts 88 and 90 (FIG. 3) separated by insulating material 92. It is convenient to form the recess 80 in the insulating material 92, which therefore is given a thickness corresponding to the length of the body 12 of the microdiode. The parts 88 and 90 have lead wires 94 and 95 extending therefrom, and the entire pedestal may be mounted on insulating material indicated at 96.

The circuit for checking polarity may be exceedingly simple, and referring to FIG. 8, a battery 98, or any other convenient D.C. source, is connected in series with the pedestal 88 and 90, and in series with a lamp 100 or other desired indicator. When the diode is properly polarized it transmits current, and the lamp lights. When the diode is improperly polarized the lamp does not light, and the operator is thereby warned to reverse the diode before marking it.

Reverting to FIG. 2, the eyes 44 are preferably yieldably mounted. In the present case each eye is carried on an upright shank which is vertically slidable in bar 46. The shank carries a light compression spring 102, permitting the eye to move upward in the event of undue tension on the wire.

To keep the wires individually and independently taut, the reels 36 preferably are not secured together, and each is provided with its own friction braking means. In the present case the brake comprises a shoe 104 carried at one end of leaf spring 106. The springs 106 are secured to blocks 108, which are carried on a spindle 110 and have set screws 112.

The wires leading to the takeup spools 58 are preferably cleaned, and for this purpose a cleaning device is shown at 114 (FIG. 2). This is a small metal container which is open at the top, and which is filled with a felt or other absorbent body which is wetted from time to time by the addition of a solvent or cleaning fluid.

The used wire may be rewound and reused, and in such case small supply reels may be mounted at about the location of the sheaves 48, and provided with a crank for rewinding the same. However, the very thin wire used is so inexpensive that it is found more economical to discard the wire after it has been used. It is therefore not essential to clean the wire on its way to the takeup spools 58, but the cleaning device is convenient because it makes the task of removing and replacing the takeup spools 58 less messy.

The paint or color is a marking ink which air dries and later is baked. In practice the marked diodes are placed on a tray, and the tray is moved to a baking oven.

It is believed that the construction and method of use of my improved marking machine, as well as the advantages thereof, will be apparent from the foregoing detailed description. The multiple color stripes are applied to close tolerance, with uniformity, and good quality. The stripes are distinctly separated, with no bleeding therebetween. The mark is applied with proper polarization. The operation may be performed rapidly, despite the minute size of the stripes to be applied, and if needed, the machine could apply even smaller stripes at smaller spacing than here mentioned as a specific example, until so small that the naked eye is no longer able to distinguish the colors.

It will be apparent that while I have shown and described the marking machine in a preferred form, changes may be made in the structure shown, without departing

from the scope of the invention as sought to be defined in the following claims.

I claim:

1. The method of applying color coded stripes to miniature components which includes first coating a plurality of thin filaments with appropriate color, there being one filament for each stripe of the color code, guiding the coated filaments very close to one another in collateral relation, and simultaneously moving all of the coated filaments laterally into contact with and then away from a component which is to be color coded.

2. The method of applying color coded stripes to miniature electronic components which includes first coating a plurality of thin filaments with appropriate color, there being one filament for each stripe of the color code, guiding the coated filaments very close to one another in collateral relation, simultaneously moving all of the coated filaments laterally into contact with and then away from an electronic component which is to be color coded, moving all of the filaments simultaneously lengthwise a small amount to present new segments of the color coated filaments, again moving all of the filaments laterally into contact with another electronic component to be color coded, and so on.

3. Apparatus for applying color coded stripes to miniature components, said apparatus comprising means to coat a plurality of thin filaments with appropriate color, there being one filament for each stripe of the color code, means to guide the coated filaments very close to one another in collateral relation, and means to simultaneously move all of the coated filaments laterally into contact with and then away from a component which is to be color coded.

4. Apparatus for applying color coded stripes to miniature electronic components, said apparatus comprising means to coat a plurality of thin filaments with appropriate color, there being one filament for each stripe of the color code, means to guide the coated filaments very close to one another in collateral relation, means to simultaneously move all of the coated filaments laterally into contact with and then away from an electronic component which is to be color coded, and means to move all of the filaments simultaneously lengthwise a small amount to present new segments of the color coated filaments, whereby the filaments may be cyclically moved longitudinally and laterally into contact with successive electronic components to be color coded.

5. Apparatus for applying color coded stripes to miniature electronic components, said apparatus comprising a pedestal to support and expose a component to receive the color code marking, a mounting plate carrying a plurality of reels of thin wire, one for each stripe, a plurality of ink containers each terminating at the bottom in a long thin tube having an inside diameter slightly greater than the diameter of the wire, a spacer having shallow grooves at the desired spacing of the stripes, guide means to guide the wires from the reels through the containers and tubes to the spacer, a plurality of takeup spools for receiving the wires leaving the spacer, said pedestal and mounting plate being relatively movable to bring the coated spaced wires against the component, and means to advance the takeup spools slightly for each printing movement of the plate and pedestal.

6. Apparatus as defined in claim 5, in which the ink containers and tubes are angularly adjustable in the plane of the path of the wire, and are so adjusted that the tube ends bears against and leaves uncoated that side of the wire which engages the spacer.

7. Apparatus as defined in claim 5, which the pedestal has two conductive sides insulated from one another, one side receiving one lead wire and the other side receiving the other lead wire of the component, and in which there are electrical connections from said pedestal sides to a polarity testing circuit, whereby the operator may check the polarity of the component before marking the same.

8. Apparatus as defined in claim 5, in which each container and tube is the body and needle of a hypodermic syringe.

9. Apparatus for applying color coded stripes to miniature electronic components, said apparatus comprising a pedestal to support and expose a component with a lead wire to receive the color code marking, a mounting plate carrying a plurality of reels of thin wire, one for each stripe, a plurality of ink containers each terminating at the bottom in a long thin tube having an inside diameter slightly greater than the diameter of the wire, a spacer having shallow grooves at the desired spacing of the stripes, guide means to guide the wires from the reels through the containers and tubes to the spacer, a plurality of takeup spools for receiving the wires leaving the spacer, said pedestal and mounting plate being relatively movable to bring the coated spaced wires against the lead wire of the component, resilient means urging the pedestal and plate apart, manual means to move them toward one another, and means to advance the takeup spools slightly for each printing movement of the plate and pedestal, said means including a ratchet wheel for turning the spools and a pawl engaging the ratchet wheel.

10. Apparatus for applying color coded stripes to miniature electronic components, said apparatus comprising a pedestal to support a component with a lead wire exposed to receive the color code marking, a mounting plate carrying a plurality of reels of thin wire, one for each stripe, a plurality of ink containers each terminating at the bottom in a long thin tube having an inside diameter slightly greater than the diameter of the wire, a spacer wheel having shallow grooves at the desired spacing of the stripes, guide means to guide the wires from the reels through the containers and tubes to the spacer wheel, a plurality of takeup spools for receiving the wires leaving the spacer wheel, said pedestal and mounting plate being relatively movable to bring the coated spaced wires at the spacer wheel against the lead wire of the component, and means to advance the takeup spools slightly for each printing movement of the plate and pedestal.

11. Apparatus as defined in claim 10, in which the ink containers and tubes are angularly adjustable in a plane perpendicular to the axis of the spacer wheel, and are so adjusted that the tube end bears against and leaves uncoated that side of the wire which engages the spacer wheel.

12. Apparatus as defined in claim 10, in which the pedestal has two conductive sides insulated from one another, one side receiving one lead wire and the other side receiving the other lead wire of the component, and in which there are electrical connections from said pedestal sides to a polarity testing circuit, whereby the operator may check the polarity of the component before marking the same.

13. Apparatus for applying color coded stripes to miniature electronic components, said apparatus comprising a pedestal to support a component with a lead wire exposed to receive the color code marking, a mounting plate carrying a plurality of reels of thin wire, one for each stripe, a plurality of ink containers each terminating at the bottom in a long thin tube having an inside diameter slightly greater than the diameter of the wire, a spacer wheel having shallow grooves at the desired spacing of the stripes, guide means to guide the wires from the reels through the containers and tubes to the spacer wheel, a plurality of takeup spools for receiving the wires leaving the spacer wheel, said pedestal and mounting plate being relatively movable to bring the coated spaced wires at the spacer wheel against the lead wire of the component, resilient means urging the pedestal and plate apart, manual means to move them toward one another, and means to advance the takeup spools slightly for each printing movement of the plate and pedestal, said means including a ratchet wheel for turning the spools and a pawl engaging the ratchet wheel.

14. Apparatus for applying color-coded stripes to miniature electronic components, said apparatus comprising a pedestal to support a component with a lead wire exposed to receive the color code marking, a mounting plate carrying a plurality of reels of thin wire, one for each stripe, a plurality of ink containers each terminating at the bottom in a long thin tube having an inside diameter slightly greater than the diameter of the wire, a spacer wheel having shallow grooves at the desired spacing of the stripes, guide means to guide the wires from the reels through the containers and tubes to the spacer wheel, a plurality of takeup spools for receiving the wires leaving the spacer wheel, said mounting plate being movable downward to bring the coated spaced wires at the spacer wheel against the lead wire of the component, and means to advance the takeup spools slightly for each printing movement of the plate.

15. Apparatus as defined in claim 14, in which the ink containers and tubes are angularly adjustable in a plane perpendicular to the axis of the spacer wheel, and are so adjusted that the tube end bears against and leaves uncoated that side of the wire which engages the spacer wheel.

16. Apparatus as defined in claim 14, in which the pedestal has two conductive sides insulated from one another, one side receiving one lead wire and the other side receiving the other lead wire of the component, and in which there are electrical connections from said pedestal sides to a polarity testing circuit, whereby the operator may check the polarity of the component before marking the same.

17. Apparatus for applying color coded stripes to miniature electronic components, said apparatus comprising a pedestal to support a component with a lead wire exposed to receive the color code marking, a mounting plate carrying a plurality of reels of thin wire, one for each stripe, a plurality of ink containers each terminating at the bottom in a long thin tube having an inside diameter slightly greater than the diameter of the wire, a spacer wheel having shallow grooves at the desired spacing of the stripes, guide means to guide the wires from the reels through the containers and tubes to the spacer wheel, a plurality of takeup spools for receiving the wires leaving the spacer wheel, said mounting plate being movable downward to bring the coated spaced wires at the spacer wheel against the lead wire of the component, resilient

means urging the plate upward, manual means to move the plate downward, and means to advance the takeup spools slightly for each printing movement of the plate.

18. Apparatus for applying color coded stripes to miniature electronic components, said apparatus comprising a pedestal to support a component with a lead wire exposed to receive the color code marking, a mounting plate carrying a plurality of reels of thin wire, one for each stripe, a plurality of ink containers each terminating at the bottom in a long thin tube having an inside diameter slightly greater than the diameter of the wire, a spacer wheel having shallow grooves at the desired spacing of the stripes, guide means to guide the wires from the reels through the containers and tubes to the spacer wheel, a plurality of takeup spools for receiving the wires leaving the spacer wheel, said mounting plate being movable downward to bring the coated spaced wires at the spacer wheel against the lead wire of the component, resilient means urging the plate upward, manual means to move the plate downward, and means to advance the takeup spools slightly for each printing movement of the plate, said means including a ratchet wheel for turning the takeup spools and a pawl on the plate engaging the ratchet wheel and so faced as to move the ratchet wheel on upward movement of the plate, said plate being pivoted for movement on the axis of the spools and ratchet wheel.

19. Apparatus as defined in claim 18, in which the ink containers and tubes are angularly adjustable in a plane perpendicular to the axis of the spacer wheel, and are so adjusted that the tube end bears against and leaves uncoated that side of the wire which engages the spacer wheel.

20. Apparatus as defined in claim 18, in which the pedestal has two conductive sides insulated from one another, one side receiving one lead wire and the other side receiving the other lead wire of the component, and in which there are electrical connections from said pedestal sides to a polarity testing circuit, whereby the operator may check the polarity of the component before marking the same.
